UNITED STATES PATENT OFFICE.

WILLIAM HERRICK, OF CHICAGO, ILLINOIS, ASSIGNOR TO THE MORGAN & WRIGHT, OF SAME PLACE.

DESIGN FOR A HAIR-SHEDDER.

SPECIFICATION forming part of Design No. 33,088, dated August 14, 1900.

Application filed June 27, 1900. Serial No. 21,852. Term of patent 14 years.

To all whom it may concern:

Be it known that I, WILLIAM HERRICK, a citizen of the United States, residing at Chicago, county of Cook, State of Illinois, have 5 invented and produced a certain new and original Design for Hair-Shedders, of which the following is a specification, reference being had to the accompanying drawings, forming part thereof.

o In the drawings, Figure 1 is a perspective showing the back of a hair-shedder embodying my design. Fig. 2 is a cross-section of the hair-shedder formed in accordance with my design. Fig. 3 is a perspective showing 5 the face of the hair-shedder.

As illustrated, the hair-shedder is rectangular in form, being composed of a back A, parallel webs B, and transverse or end webs C. The back of the hair-shedder is formed 0 with an arch-like guard D. In cross-section

the ribs or webs B appear at right angles to the back A.

The essential feature of my design consists in the hair-shedder having its face formed with a series of parallel ribs or webs connected at their ends by transverse or end webs and having its back formed with an arch-like guard or handle. 25

Having described my invention, what I claim as new, and desire to secure by Letters 30 Patent, is—

The design for a hair-shedder, substantially as shown and described.

In testimony whereof I have signed my name to this specification in the presence of 35 two subscribing witnesses.

WILLIAM HERRICK.
